INFANT'S CRIB

Abraham G. Feldman, Chicago, Ill., assignor to
Storkline Furniture Corporation, Chicago, Ill.,
a corporation of Illinois

Application September 2, 1950, Serial No. 12,035

Term of patent 7 years

(Cl. D5—5)

To all whom it may concern:

Be it known that I, Abraham G. Feldman, a citizen of the United States, residing in Chicago, in the county of Cook, and State of Illinois, have invented a new, original, and ornamental Design for an Infant's Crib, of which the following is a specification, reference being had to the accompanying drawing forming part thereof, in which:

The single figure of the drawing is a perspective view taken from one end and somewhat to one side of an infant's crib embodying my new design, a mattress being shown in dotted outline.

It will be noted that the head end panel of the crib is similar in design to the front end panel adjacent its upper end, but is materially shorter than the foot panel as it terminates at the mattress line, as shown.

I claim:

The ornamental design for an infant's crib, substantially as shown and described.

ABRAHAM G. FELDMAN.
